BRAKE RIGGING

Filed March 10, 1927

2 Sheets-Sheet 2

Inventor:
John W. Foyle,
Bydeworth, Lu., Corinth, Miss.
Attest,

UNITED STATES PATENT OFFICE

JOHN W. FOYLE, OF KANSAS CITY, MISSOURI, ASSIGNOR TO GUSTIN-BACON MANUFACTURING CO., OF KANSAS CITY, MISSOURI, A CORPORATION OF MISSOURI

BRAKE-RIGGING

Application filed March 10, 1927. Serial No. 174,191.

My invention relates, more particularly, to 5 brake-rigging for railway cars involving mechanism by which the slack between brake- mechanism and the actuating element there- for, as for example and more particularly, a manually operable element, may be quickly taken up and thereafter sufficient power ex- 10 ereted by the actuating element to produce a degree of pressure of the brake shoes against the wheels necessary and desirable to effect proper setting of the brakes.

My object is to provide a novel, simple, in- 15 expensive and positively operating mech- anism for accomplishing the purposes stated which may be incorporated in brake-rigging operated manually only, or brake-rigging op- 20 erated selectively, either by power as for ex- ample compressed air, or manually.

Referring to the accompanying drawings: 25 Figure 1 is a broken plan sectional view of the frame structure of a railway car equipped with brake rigging in accordance with my invention. Figure 2 is a broken view in sec- 30 tional elevation of the structure shown in Fig. 1, the section being taken at the irregu- 35 lar line 2—2 on Fig. 1 and viewed in the di- 40 rection of the arrow. Figure 3 is an enlarged 45 sectional view taken at the line 3 on Fig. 2 and viewed in the direction of the arrow; and 50 Figure 4, an enlarged sectional view taken at the irregular line 4—4 on Fig. 1 and viewed in the direction of the arrow.

In the construction shown the member 55 through the medium of which the brake- rigging mechanism is operated to set the 60 brakes, and which may be the hand brake rod commonly provided in air-brake mechanism and operatively flexibly connected with the 65 push rod thereof and by which the brakes are set manually, is represented at 5, it being understood that when this rod 5 is shifted to the right in Figs. 1 and 2 the brake me- 70 chanism controlled thereby is moved to braking position.

One of the center sills and an end sill of 75 the car are represented, respectively, at 6 and 80 7, the latter rotatably supporting a vertical 85 brake-staff 8 equipped at its upper end, in ac- 90 cordance with common practice, with a 95 manually operable element, as for example a

hand wheel represented by dotted lines in Fig. 1 at 9.

Interposed between the member 5 and the 55 brake-staff 8 is my improved mechanism which comprises a sheave 10 rotatably mounted on a journalling pin 11 secured in the outer extremities of vertically spaced bracket arms 12 and 13 rigidly connected with the sill member 6 and extending laterally therefrom. Extending around the 60 sheave 10 is a flexible element, shown as a chain 14, attached at one end to the sheave, as though the medium of a bolt 15 carried by the sheave and extending through the terminal link of the chain, the other end of this 65 chain being rigidly connected with the brake- staff 8, as indicated at 16, the arrangement of the parts just described being such that when the brake-staff 8 is rotated in clockwise direc- 70 tion in Fig. 1 the chain will be wound upon the brake-staff and unwound from the sheave 10 thereby rotating the latter in clockwise direction in this figure. The hub portion of the sheave 10 is provided at one end with a pinion 17 and at its other end with a seg- 75 mental gear 18 of considerably larger radius than the pinion 17, this pinion and segmen- tal gear being shown as formed integrally with the hub portion of the sheave.

The pinion 17 and segmental gear 18 are 80 adapted for cooperation with racks 19 and 20, respectively, with which they successively engage in the operation of the mechanism, the racks 19 and 20 being operatively con- 85 nected with the rod 5 preferably through the medium of a yoke-shaped member 21 carrying these racks on its yoke arms and pivotally connected at 22 with the rod 5. The arms of the yoke 21 contain slots 23 and 24 through 90 which the ends of the hub of the sheave 10 extend, whereby this yoke is supported on the sheave structure, while adapted for movement relative thereto in a direction crosswise of the pivot 11.

The operation of the mechanism is as fol- 95 lows: Assuming that the parts of the mecha- nism are in the position shown in the draw- 100 ings, in which position the brakes controlled thereby are released, rotation of the brake- staff 8 in clockwise direction in Fig. 1 rotates

the sheave 10 and consequently the pinion 17 and segmental gear 19 in clockwise direction in this figure. In this normal, brake-released, position of the parts the segmental gear 18 is in mesh with one end of the rack 20, and therefore when the staff 8 is rotatable as stated the member 21 and rod 5 are shifted to the right in Figs. 1 and 2 to take up the slack in the brake mechanism. As 10 the gear 18 moves out of mesh with the rack 20, in the continued rotation of the brake-staff 8, the rack 19 moves into mesh with the pinion 17 so that the remainder of the movement of the member 21 and rod 5 to the right 15 in Fig. 2, is effected through this pinion-drive, in which operation the brakes are moved to set condition.

Inasmuch as the radius of the segmental gear 18 is greater than the radius of the pinion 17, the member 21 and rod 5 are actuated from the brake-staff 8 initially at a greater speed and with the exertion of less leverage than during their operation by the engagement of the pinion 17 with the rack 19. Thus 20 25 the operator in manually rotating the brake-staff 8 may quickly take up the slack which exists in the brake-rigging, and the taking up of which does not require much power, and immediately thereafter, by the engagement 30 of the rack 19 with the pinion 17, apply the pressure necessary to properly set the brakes.

In accordance with the preferred arrangement of the parts as illustrated, the rack 19 35 is arranged substantially in line with the rod 5 which is an advantage inasmuch as the application of force thereto, by the pinion 17, is substantially in line with the rod, thereby avoiding canting of the rack.

40 While I have illustrated and described a particular construction embodying my invention, I do not wish to be understood as intending to limit it thereto as the same may be variously modified and altered without 45 departing from the spirit of my invention.

What I claim as new, and desire to secure by Letters Patent, is:

1. In brake-rigging, the combination of a 50 hand-operated element, a shiftable member adapted, when shifted, to actuate the brake mechanism, a rotatable member having sets of gear teeth located at opposite sides of said rotatable member and at different distances from said axis, a pair of racks by which said shiftable member is operated and adapted to respectively engage with said sets of gear teeth in succession in the rotation of said rotatable member, and means actuated by said element for rotating said rotatable member.

60 2. In brake-rigging, the combination of a hand-operated element, a shiftable member adapted, when shifted, to actuate the brake mechanism, a rotatable member having sets of gear teeth located at opposite sides thereof 65 and at different distances from said axis, a

third member operatively engaging with said shiftable member and provided with a pair of racks located at opposite sides of said rotatable member, said third member being slotted and said racks being adapted to respectively engage with said sets of gear teeth in succession in the rotation of said rotatable member, means actuated by said element for rotating said rotatable member, and means engageable with said third member at the slotted portion of the latter for ensuring engagement of said sets of gear teeth with said racks.
